(57) **CLAIM**

The ornamental design for a LED projector light, as shown and described.

DESCRIPTION

FIG. 1 is a front-right perspective view of a LED projector light.

FIG. 2 is a back-right perspective view of the LED projector light.

FIG. 3 is a right elevation view of the LED projector light.

FIG. 4 is a left elevation view of the LED projector light.

FIG. 5 is a front elevation view of the LED projector light.

FIG. 6 is a back elevation view of the LED projector light.

FIG. 7 is a top plan view of the LED projector light; and,

FIG. 8 is a bottom plan view of the LED projector light.

The broken lines shown in the drawings depict portions of the LED projector light that form no part of the claimed design.
